UNITED STATES PATENT OFFICE.

CHRISTOPHER L. DALY, OF PEORIA, ILLINOIS.

REFRIGERATING APPARATUS.

SPECIFICATION forming part of Letters Patent No. 780,600, dated January 24, 1905.

Application filed June 15, 1903. Serial No. 161,509.

To all whom it may concern:

Be it known that I, CHRISTOPHER L. DALY, a citizen of the United States, residing at Peoria, in the county of Peoria and State of Illinois, have invented certain new and useful Improvements in Refrigerating Apparatus; and I do hereby declare that the following is a full, clear, and exact description of the invention, which will enable others skilled in the art to which it appertains to make and use the same.

This invention has reference to mechanism for improving the circulation in refrigerator-cars and other refrigerating apparatus.

15 The invention relates more especially to that class of refrigerator-cars provided with ice-boxes at their opposite ends having wire netting or screens at the top and with suitable openings in the bottom portions thereof, which 20 permit cold air to leave at the bottom of the box, circulate into the body of the car, and force warm air into the top of the ice-boxes. By the use of the ice-boxes alone the product which is placed close to the boxes receives a 25 much stronger refrigeration than that loaded in the center of the car or adjacent to the doors, where more or less hot air enters.

My invention therefore has for its primary object to provide mechanism which will of 30 itself create a current and siphon the hot air out of the center of the car and into the ice-boxes at the ends thereof; further, making such mechanism adjustable for the purpose of giving a strong or mild circulation.

35 With these ends in view my invention consists in certain features of novelty in the construction, combination, and arrangement of parts whereby the said objects and certain other objects hereinafter appearing are accomplished, all as will now be fully described 40 with reference to the accompanying drawings, and more particularly pointed out in the claims.

In the said drawings, Figure 1 is a vertical 45 longitudinal section of a refrigerator-car with my improvements attached thereto. Fig. 2 is a detail of certain parts of the device.

1 represents the usual outer wooden wall of the refrigerator-car body lined with a false 50 wall 2, and 3 indicates the bottom of the car,

which is also lined with wall 2. Extending over the same, as shown, and overlying said bottom and wall 2 is a false bottom 4, composed of a skeleton frame or number of slats, as usual, forming the air spaces or shafts 5, 55 communicating with an air-passage 6, which at its opposite ends communicates with the lower open ends of ice-boxes to be described. Between the outer walls bottom and false wall 2 is filled with a suitable insulation 7 in 60 the ordinary manner.

The ice-boxes are indicated as 8, having the inner presented walls 9 of suitable material, preferably galvanized metal, and at or near the bottom of the boxes is provided the racks 65 10 for supporting ice and through which air-currents may circulate and enter the passage 6, leading to the body of the car in manner described. The upper end of the wall 9 is open, and such opening is covered with a wire 70 netting or screen 11, through which the hot air enters from the body of the car and passes down into the ice-boxes.

12 indicates a casing forming a false roof, wall, or air-shaft of a refrigerating car or 75 apparatus, preferably supported on an incline when using it in a car, but disposing it in any suitable position in other apparatus by means of which the desired refrigeration may be obtained. The same is used in series. In 80 a car the ends of the air-shaft are carried close up to the top of the car and adjacent to the screened portions of the ice-boxes and pivoted to the sides of the car at a point 13. When two shafts are employed, as in Fig. 1, 85 the adjacent ends of opposite shafts are in close proximity to each other and disposed so that they are approximately in the center of the car, and to the end of each shaft at 14 is attached a chain 15 for raising or lowering 90 the inner adjacent ends of the shafts 12 and fix the same in such adjusted positions by catching the free ends of the chains to hooks 16 in the top of the car. By this means the shafts may be swung on their pivots 13 and 95 the incline of the shafts made to correspond or not and placed at any suitable angle.

The air-shafts are composed of the side walls 17 and the upper and lower coverings 18 and 19, leaving the open ends 20 and 21. In the 100

lower covering or wall 19 I provide the openings 22, covered by the overlying lips or deflectors 23, which may be, as shown, an integral part with the lower wall 19 and curved 5 upwardly and forwardly, as seen, to provide the covering-plates 23, and by such arrangement of openings and covering-plates a current is established through each of said openings, which lead to a current established by 10 such a circulation in the shaft above the plates or deflectors 23 and indicated as 24. The openings are arranged and disposed in the wall of the shaft so as to leave a somewhat-extended solid lower wall 25, leading from 15 the end of the shaft adjacent to the ice-boxes, which will prevent the admission of too much air in the forward ends of the shafts and block the passage of air from the center of the car, where it is most desired to take it from. Thus 20 a current being established through the shaft and the openings 22 thereof, which are distributed in the bottom of the shaft to form air-shafts from different points of the car, the dead air is siphoned from all parts of the car 25 through the inner adjacent ends of the shafts and openings thereof and discharged into the ice-boxes, as is apparent. The heated air being cooled descends into the boxes and finds its way out into the passage 6 and up through 30 the slatted bottom 4, following the air-currents established as the air becomes heated. The natural tendency of the heat being to rise, in a car of this character minus the air-shafts or similar devices to produce a circulation 35 there is a tendency to form a vacuum in the center of the car which heats the product, and it is this dead air which I aim to convey away. The formation of the shaft, raising or lowering the same, decreases or increases the 40 circulation, and the arrangement of its various

openings and coverings establishes reverse-currents from the body of the car which are not interfered with and do not cross each other, which of course would destroy the object sought after.

45

Having thus fully described my invention, what I claim, and desire to secure by Letters Patent of the United States, is—

1. In combination with a car having ice-compartments, air-shafts extending from the 50 upper end of the compartments to a point approximately the center of the car, pivoted at their outer ends to the body of the car and means at their inner ends for raising and lowering the shafts and for fixing them in their 55 raised or lowered positions, a bottom for said shafts extending from the outer end inwardly to a suitable point, and the remainder of the shaft provided at intervals with air-inlets, substantially for the purposes set forth.

60

2. In combination with a car having ice-compartments, a pair of air-shafts having their outer ends pivoted to the sides of the car adjacent to the ice-compartments and their inner matching ends extending to a point approximately the center of the car, means for supporting the inner ends of the air-shafts in adjusted positions, a bottom for the air-shafts provided at intervals with air-inlets and deflectors overlying the said air-inlets adapted 70 to deflect the air entering the air-inlets of the air-shaft from the body of the car to the opposite ends thereof, substantially as specified.

65

In testimony whereof I affix my signature in 75 presence of two witnesses.

CHRISTOPHER L. DALY.
